A. A. RUTTAN

TWO-COMPARTMENT RECEPTACLE

Filed May 12, 1927

FIG. 1.

FIG. 2.

FIG. 4.

INVENTOR,
Alfred A. Ruttan,
BY R. L. Stinchfield
Euseah Stewart,
ATTORNEYS.

UNITED STATES PATENT OFFICE.

ALFRED A. RUTTAN, OF ROCHESTER, NEW YORK, ASSIGNOR TO EASTMAN KODAK COMPANY, OF ROCHESTER, NEW YORK, A CORPORATION OF NEW YORK.

TWO-COMPARTMENT RECEPTACLE.

Application filed May 12, 1927. Serial No. 190,860.

This invention relates to receptacles and particularly for two-part receptacles or containers designed for holding two chemicals such as may be used together. One object 5 of my invention is to provide a container in which each receptacle may be separately filled and closed so that danger of prematurely mixing the contents is eliminated. Another object is to provide a strong light 10 container which may be readily shipped without danger of the contents of the two containers becoming prematurely contaminated. Another object is to provide a receptacle with a relatively cheap inner container 15 which may be made of fibrous materials, such as press or fiber board, and to provide a suitable construction for supporting the inner container in the outer container, said supporting device forming a seat for a 20 cover for the inner container. Other objects will appear hereinafter from the following specification, the novel features being particularly pointed out in the claims at the end thereof.

25 Coming now to the drawings wherein like reference characters denote like parts throughout,

Fig. 1 is a half section, half side elevation of parts of a container constructed in accordance with and embodying a preferred form of my invention, parts of the container being shown in broken lines;

Fig. 2 is a part top plan view of the container shown in Fig. 1, the outer container 30 and cover being omitted for clearness, and

Figs. 3 and 4 are enlarged sectional details of parts of the container structure.

As shown in Fig. 1, the preferred embodiment of my invention consists of an outer 40 container 1, which is shown in broken lines for clearness. This container may have a bottom wall 2 and flat upper rolled edge 3.

A part-cover 4 frictionally engages in container 1, part 4 including a rolled outer 45 edge 5 and spaced walls 6 and 7, the former engaging container 1. Part-cover 4 is an annular member and the inside portion is formed, as best shown in Fig. 3, at 8 to provide an offset wall 12 spaced from wall 10 by an angularly disposed wall 9.

The offset walls 8 and 10 engage walls 11 and 13 of a ring 11, and these walls are spaced by a wall 12 which is not in contact with wall 10, see Fig. 4, where the dotted lines at b show where wall 11 is bent in

assembling. The ring is crimped at 14 over the edge 15 of the inner container 16, the lower edge 17 thereof being engaged by a crimped edge 18 of the bottom wall 19.

I prefer to form the inner container of 60 fibrous material which is light and strong, such as tubularly wound cardboard, as this for most purposes is a suitable material, and with the other parts above mentioned made from sheet metal forms a sufficiently strong 65 receptacle. I do not, however, wish to be limited to the material mentioned except as noted in the following claims.

Having thus described my invention, what I claim as new and desire to secure by Letters Patent is:

1. In a two-part receptacle, the combination with an outer container, of an inner container adapted to be supported by a part-cover for the outer container, said part-cover including an annular member having an offset wall adapted to frictionally engage the outer container, and including a pair of spaced inner walls connected by an annular wall, a channel shaped ring having two 80 walls engaging the spaced inner walls and having an edge of one wall bent upon one of the walls whereby a reinforced double walled opening is provided, an inner container supported by the ring, and a cover 85 for the inner container adapted to engage the double walled opening.

2. In a two-part receptacle, the combination with an outer container of an inner container adapted to be supported by a part-cover for the outer container, said part-cover including an annular member having an offset wall adapted to frictionally engage the outer container, and including a pair of spaced inner walls connected by an angularly disposed wall, a channel shaped ring having walls engaging the spaced walls of the part-cover, and a wall spaced from the angularly disposed wall thereof whereby a reinforced support is provided, an inner receptacle having a periphery crimped on said ring and a cover for closing the inner receptacle.

3. In a two-part receptacle, the combination with an outer container, of an inner container adapted to be supported by a metallic part-cover for the outer container, said part-cover including a pair of inner spaced walls, connected by a wall angularly disposed with regard to the two walls, said 110

inner container being of composition material, a metallic ring crimped upon a periphery of the inner container, said ring having a pair of walls engaging the spaced offset walls of the part-cover, one wall being bent upon a wall of the part-cover whereby a reinforced opening is provided for loading

the inner container, and a cover adapted to engage the walls of the opening, the inner receptacle and part-cover forming a complete closure for the outer container. ¹⁰

Signed at Rochester, New York this 5th day of May, 1927.

ALFRED A. RUTTAN.
